UNITED STATES PATENT OFFICE.

ADOLF ODKOLEK VON AUGEZD, OF VIENNA, AUSTRIA-HUNGARY.

AUTOMATIC FIREARM.

No. 799,884.

Specification of Letters Patent.

Patented Sept. 19, 1905.

Application filed June 11, 1900. Serial No. 19,892.

To all whom it may concern:

Be it known that I, ADOLF ODKOLEK VON AUGEZD, a subject of the Emperor of Austria-Hungary, residing at Vienna, in the Province 5 of Lower Austria, in the Empire of Austria-Hungary, have invented certain new and useful Improvements in Firearms for Firing Single Shots and Automatic Continuous Fire; and I do hereby declare the following to be 10 a full, clear, and exact description of the invention, such as will enable others skilled in the art to which it appertains to make and use the same, reference being had to the accompanying drawings, and to letters and figures of reference marked thereon, which form 15 a part of this specification.

This invention has relation to breech-loading guns, and more particularly to that type known as "gas-actuated" guns, in which 20 the breech is opened by the pressure of the gases of discharge and the breech mechanism moved into loading and firing position.

The essential object of this invention lies in the simplification of the breech mechanism, 25 which enables me to strengthen the elements thereof, reduce their number, and thereby increase the efficiency and durability of the gun.

That my said invention may be fully understood, I will describe the same in detail, reference being had to the accompanying drawings, in which—

Figures 1 and 2 are fragmentary longitudinal sectional views of the gun, showing the breech closed and open, respectively. Fig. 3 is a top plan view of Fig. 1; Fig. 4, a vertical section through the breech-casing and cartridge-feeding appliances. Fig. 5 is a like section on line A B of Fig. 2. Fig. 6 is a detail view; Fig. 7, a fragmentary side elevation, partly in section; Fig. 8, a vertical section of the gun-barrel and gas-tube, showing means for cooling the barrel; and Fig. 9 is a sectional detail view of a modified connection between the gas-tube and actuating-piston.

In the drawings, *b* indicates the breech-casing, the general construction of which is shown in Figs. 4 and 5, it being closed at top and having an upper chamber *a*, which is cylindrical at its forward end and forms a receiver *g*. The casing *b* has also a vertical comparatively narrow guideway *d*, opening into said chamber *a* and enlarged near its upper end into a substantially circular guideway *h*, in which is guided the actuating-bar *g*, hereinafter referred to. The guideway *d* below the guideway *h* does not extend to the

rear end of the breech-casing, as shown in Fig. 1, but only a sufficient distance to permit the rearward movement of the aforesaid actuating-bar *g*, and at its said rear end the 60 casing has a shoulder-rest *k*.

In the upper portion of the passage *d* below the chamber *a*, at a distance from the breech of the gun-barrel *B* equal or substantially equal to the length of the breech-bolt 65 *c*, are arranged two abutments *e*, facing each other and inserted through the vertical walls of the breech-casing *b*, Fig. 5. The lower part of the breech-casing *b* from the trigger-guard *y* nearly to the end of the lower portion of the vertical passage *d* is closed by a slide-plate *7*, connected to the vertical walls of said casing by tongue-and-groove joint, the plate having at its forward end a handle *z*, projecting from its under face, and a lug 70 *9*, projecting from its upper face at such a point as to lie in front of a lug *10* at the rear end of the actuating-bar *g* when in its forward position, Fig. 1. The plate *7* is locked against endwise motion by a two-armed lever 75 *8*, fulcrumed in a longitudinal slot in the plate *7*, the rear end *8* of said lever abutting against the forward face of the fixed rear portion *b'* of the bottom of casing *b*, while the forward end of said lever projects from the under side 80 of said plate *7*, so that by pressure on said forward end the rear end of said lever is disengaged from its abutment and the plate is free 85 to slide rearwardly.

The breech-bolt *c* is cylindrical and contains 90 the firing-pin *l*, and at its rear end said breech-bolt has on either side a rearwardly-projecting lug *c'*, fitting corresponding recesses *i'* in opposite sides of a vertical projection *i* on the rear end of the actuating-bar *g*, and at its rear 95 end the said breech-bolt *c* has a short longitudinal slot *c*², Fig. 2, and at the forward end of said slot a lug *s*.

At its rear end the firing-pin *l* has a lug *m*, projecting into a notch *g'* on the actuating-bar *g* in front of its projection *i*. The breech-bolt *c* has also a lug *f*, which projects into a recess *g*² in the upper face of the actuating-bar *g*, said recess being of such a length relatively to the length of the lug *f* as to enable 105 the actuating-bar to move rearwardly or forwardly independently of the breech-bolt *c* for a short distance for purposes hereinafter explained, said actuating-bar having at its rear end the lug *10*, already referred to, a lug *x* at 110 its forward end, and a lug *t* on its upper face.

To the trigger *1* is pivoted a tumbler *2* held

in a normal position by a spring 2', the nose of said tumbler engaging the forward end of a sear *w*, consisting of a two-armed lever pivoted at 4 in the breech-casing *b*, the rearward arm of which sear lies in the path of the lug *x* at the forward end of the actuating-bar *g* and is held in a normal position by a pin 6, projecting through a segmental slot in one of the vertical walls of the breech-casing *b*, to which is pivoted at 4, Fig. 6, a lever 5, to which said pin is secured, so that by depressing said lever the rear arm of the sear is depressed and held out of the path of the lug *x* on the forward end of the actuating-bar *g*.

15 In the chamber *a* of the breech-casing *b* in rear of the projection *i* of the actuating-bar *g* is arranged the mainspring *j*, mounted on a tube *v'*, secured to the rear wall of said breech-casing and containing a buffer-spring and a 20 buffer *v*, whose movements in either direction are limited by longitudinal slots *v**, into which project pins *v** on the buffer *v*.

25 The breech-bolt *c* has rectilinear motion in the receiver *a'* and chamber *a*, and in view of the location of the abutments *e* below said chamber *a* it is necessary that the rear end of said breech-bolt be depressed when in position to close the breech, Fig. 1, and that said rear end be again raised above said abutments before it can be moved rearwardly. On the other hand, inasmuch as the firing-pin is connected to and projected and retracted by the actuating-bar *g* it is necessary that the latter should have motion independently of said breech-bolt both rearwardly and forwardly. 30 This is accomplished by the construction of the breech-casing wherein the rear end of the breech-bolt *c* can drop in front of the abutments *e* and by reason of the recesses *i'* and 35 lugs *c'* and the length of the recess *g** in actuating-bar *g* relatively to lug *f* on the breech-bolt *c*, whereby said actuating-bar is enabled to move forward a sufficient distance after the breech-bolt has closed the breech and dropped 40 in front of the abutments *e* to thrust the firing-pin *l* into contact with and explode the cartridge.

45 On its rearward motion the actuating-bar *g* moves a short distance independently of the breech-bolt sufficient to retract the firing-pin and at the same time move out of engagement with said breech-bolt and lift its rear end through the lugs *s* *t* clear of the abutments *e*, as hereinafter referred to.

55 In the right receiver-wall is formed a longitudinal slot *u*, Fig. 4, through which the empty cartridges are ejected by means of any well-known or suitable ejector. (Not shown in the drawings.)

60 In a cylinder *b**, formed on the breech-casing *b*, works a piston *o*, acting on the forward end of the actuating-bar *g* when impelled by the gases of discharge. The forward portion of the piston *o* is of increased diameter and 65 tubular and works on a coupling *p*, provided

with an axial bore, to which coupling is secured the gas-tube *q*. At its outer end the piston *o* has a collar *r*, that serves to limit the instroke by contact with the outer end of cylinder *b**, while the outstroke of said piston under the stress of the spring *n* coiled thereon is limited by the enlarged portion of the aforesaid coupling *p*, as shown in Fig. 1.

If desired and as shown in Fig. 9, the coupling *p* can be dispensed with, in which case 75 the piston is solid and the gas-tube abuts directly on its outer face, and to insure proper action of the gases of discharge the piston has in its outer face a concave recess in register with the correspondingly outwardly 80 flaring outlet end of the passage in gas-tube *q*. This gas-tube *q* extends along the gun-barrel *B* a suitable distance, and its outer end is in communication with the bore of said barrel in a well-known manner. 85

In the gun described the cartridges are secured to a belt 11, the free end of which passes through a vertical slot 12 in a belt-guide 13, arranged on the left-hand side of the gun at the feed-slot *a** for the receiver *a'*, the cartridges being fed through said slot and held in the path of the breech-bolt *c* by a pull on the free end of the belt below the belt-guide 13, the cartridge so held being detached from its belt and carried out of the receiver into 95 the breech by the forward movement of the breech-bolt *c* in a well-known manner.

At a suitable distance forward of the breech the barrel *B* has a radial passage 14 and an internally-screw-threaded coupling branch 100 whose axis is eccentric to said radial passage. To the coupling is screwed the nipple 16 of an elastic bulb 17, filled with a cooling fluid, the bore of the nipple being likewise eccentric to its axis of rotation and so located relatively to the radial passage 14 in the gun-barrel that when said nipple 16 is turned by means of the handle thereon to a certain extent the said passage 14 and bore of the nipple will be in register, Fig. 8, so that cooling 110 fluid can be injected into the gun-barrel by compression of the bulb 17, and, as will be readily seen, by a slight turn of the nipple 16 the bore thereof will be moved out of register with passage 14, thereby cutting off the communication between the bore of barrel *B* and the bulb 17. Obviously instead of the bulb 17 a pump can be employed. 115

The operation of the gun is as follows: Assuming that the elements of the breech mechanism are in their respective positions, Fig. 1—that is to say, in their normal position—the actuating-bar *g* is now retracted by means of the slide-plate 7, as hereinabove described, to move said bar and parts connected thereto into the position shown in Fig. 2, when the sear *w* will snap in front of lug *x* and hold the bar against forward movement. The slide-plate is now moved back into its normal position, and by a pull on 120

125 130 135

the belt 11 a cartridge C is fed into the receiver and held in the path of the breech-bolt c. A pull on the trigger 1 will move the sear w clear of the lug x on the actuating-bar g, the 5 mainspring j throwing said bar, together with the breech-bolt c, forward, the latter detaching the cartridge C from the belt 11 and carrying it into the breech of the gun. As the breech-bolt c closes the breech its rear end 10 drops in front of the abutment e. The actuating-bar g now completes its forward movement, thrusting the firing-pin into contact with the cartridge to explode the same, at which time the lugs c' at the rear end of the 15 breech-bolt c are in full engagement with the recesses z' on the projection i at the rear end of said actuating-bar g, the parts being again in their respective positions shown in Fig. 1, the rear end of the breech-bolt lug f abutting against the rear vertical wall of the recess g' in the actuating-bar g.

It will be observed that the breech-bolt, the firing-pin l, and actuating-bar g are at no time disconnected; but in order to permit the 25 rear end of the breech-bolt to drop in front of the abutments e the firing-pin and projection i must be articulated together, and this I accomplish by the notch g' in front of projection i and the lug m at the rear end of said 30 firing-pin, said notch being of sufficient depth to allow the required up-and-down movements of the rear end of the breech-bolt. It will therefore be seen that the action of the articulated actuating-bar and firing-pin is the 35 same as if said parts were rigidly connected. As the firing-pin is thrown forward the gun is discharged, and as soon as the projectile clears the gas-port leading to the gas-tube q the gases of discharge throw the piston o rear- 40 wardly and therethrough the actuating-bar g, the latter first moving independently of the breech-bolt c a sufficient distance not only to retract the firing-pin, but to move the lug t on said bar g under the lug s on the breech- 45 bolt c, thereby lifting the rear end thereof clear of the abutments e, so as to enable said breech-bolt to move back with said locking-bolt under the blow of the piston o, the parts having returned to their positions shown in 50 Fig. 2. During the rearward movement of the breech-bolt and actuating-bar the cartridge-shell is ejected, and a pull on the cartridge-belt 11 will bring a fresh cartridge C into the receiver and path of the breech-bolt, 55 the gun being ready for firing.

As is well known, the pressure of the gases of discharge, although acting on the piston momentarily only, is enormously greater than the power required to move the actuating- 60 bar and breech-bolt back against the stress of the main and buffer springs, and to avoid injury to these and to the breech mechanism I provide the means hereinabove described 65 limiting the instroke of said piston, so that its action on the actuating-bar will be but a

momentary one—much shorter than the period of action of the gases of discharge on the piston itself. It will furthermore be observed that at the time of discharge the breech-bolt c is not only locked to the breech by the abutments e, but is furthermore held against rearward or recoil movement by the mainspring j acting on the actuating-bar, whose projection i is then, as above stated, locked to said breech-bolt.

If the gun is to operate automatically, the sear w is moved out of the path of lug x on the actuating-bar g by means of the lever 5, Fig. 6, as above described, so that said bar will be thrown forward immediately after 80 reaching the limit of its backward movement under the pressure of the gases of discharge, a cartridge being of course moved into the path of the breech-bolt at each backward throw thereof and ejection of the empty cartridge-shell from the breech and receiver.

It has been stated that the breech-casing is completely closed, so that means to place the gun in operative condition are necessary—namely, means for moving the actuating-bar g from its normal position, Fig. 1, into the position shown in Fig. 2. This is effected through the plate 7, hereinbefore described, as it is obvious that if the parts are in their respective positions shown in Fig. 1 and the plate 7 is released by pressure on lever 8 said plate can be retracted by means of the handle z, the lug 9 on said plate bearing on lug 10 at the rear end of the actuating-bar g, carrying said bar along and therethrough the breech-bolt c, and as soon as the sear w snaps in front of the lug x the plate 7 can be moved back to its normal position.

The construction shown in Fig. 9 has the advantage of relieving the piston o of practically all gas-pressure the moment said piston recedes from the end of the gas-tube q, as will readily be understood, the gases then escaping into the atmosphere. Finally it may be stated that by concentrically arranging the main and buffer springs j, r and inclosing the latter in a tube extending through a considerable portion of the length of said main-spring neither of these springs is liable to lateral deflection or buckling, thereby increasing the life of both springs and insuring the smooth operation of the breech mechanism.

Having thus described my invention, what I claim as new therein, and desire to secure by Letters Patent, is—

1. The combination with the breech-casing and receiver and a breech-bolt loosely contained therein, a fixed support at the forward end of the receiver onto and off which support the forward end of the bolt is free to move and when on said support to freely swing up and down, and an abutment at the rear end of the receiver having its upper face in line with the like face of said fixed support to lock the bolt to the breech and to support

the same during its rearward movement; of an actuating-bar having to-and-fro motion below the breech-bolt and loosely connected thereto and means to lift the rear end of the bolt clear of the aforesaid abutment and support said rear end during the rearward movement of the bar and bolt.

2. The combination with the breech-casing and receiver, a cylindrical breech-bolt loosely contained therein and provided with a depending lug, a fixed support at the forward end of the receiver onto and off which the breech-bolt is free to move and swing up and down when on said support, and an abutment, at the rear end of the receiver having its upper face in line with the like face of the aforesaid support to lock the breech-bolt to the breech and to support the same during its rearward movement; of an actuating-bar having to-and-fro motion below the breech-bolt and provided with a recess into which projects the aforesaid depending lug on the breech-bolt, and means to lift the rear end of the latter clear of the aforesaid abutment and to support said rear end during the rearward movement of the bar and bolt.

3. The combination with the breech-casing and receiver, a breech-bolt loosely contained therein and having a depending lug, a firing-pin loosely contained in said bolt and having a depending lug at its rear end, a fixed support at the forward end of the receiver onto and off which support the bolt is free to move and to swing up and down when on said support, and an abutment at the rear end of the receiver having its upper face in line with the like face of the aforesaid fixed support, to lock the bolt to the breech and to support the same during its rearward movement; of an actuating-bar having to-and-fro motion below the breech-bolt and provided with a recess into which the aforesaid lug on the breech-bolt projects, said recess of greater length than said lug and provided also with a recessed portion of such depth for the depending lug on the firing-pin as to admit of the free up-and-down movement of the bolt and firing-pin without breaking the connection between said pin and bar, and means to lift the rear end of the breech-bolt clear of its abutment and to support said end during the rearward movement of the bar and bolt.

4. In a breech-loading firearm, the combination with the receiver, the breech-bolt adapted to tilt or swing in a vertical plane and provided with a cam or lug γ on its under face and with shoulders c' at its rear end, fixed

abutments for the rear end of the breech-bolt, and a firing-pin movable in said breech-bolt; of an actuating-bar constructed to engage the breech-bolt and firing-pin and move them to and fro together and to move the firing-pin independently of the bolt, said bar provided with a cam or lug t coacting with the aforesaid lug γ as described, and with a vertical projection having recesses β in its front face for the aforesaid shoulders c' on the breech-bolt, a mainspring in alinement with the receiver, acting on the rear face of the aforesaid vertical projection on the actuating-bar, means to move the latter rearwardly against the stress of the spring, and trigger-operated mechanism adapted to lock said bar against forward motion, substantially as and for the purpose set forth.

5. The combination with the actuating-bar g , and mechanism operated thereby, said bar provided with a depending lug 10 at its rear end and an under-face projection α at its forward end, the mainspring acting on said bar, and a trigger-operated sear adapted to engage the projection α when the bar is moved into its rearward position; of a slide-plate provided with a handle and a vertical projection 9 coacting with the depending lug 10 on bar g to move the latter rearwardly against the stress of the mainspring when the plate is pulled back and means to lock said plate against rearward movement, substantially as set forth.

6. The combination with the breech-casing and breech mechanism; of an actuating-bar contained wholly within said casing and provided with a depending lug at either end, a mainspring acting on the rear end of the bar to throw the same forward, a slide provided with a handle and with a vertical lug adapted to engage the depending lug at the rear end of the bar and move the same rearwardly against the stress of the mainspring by the rearward movement of the slide, a hand-operated locking-lever adapted to lock the slide against rearward motion, and a trigger-operated sear adapted to engage the depending lug at the forward end of the bar when the latter has been moved rearwardly, substantially as and for the purposes set forth.

In testimony that I claim the foregoing as my invention I have signed my name in presence of two subscribing witnesses.

ADOLF ODKOLEK VON AUGEZD.
